legends on the portion of a mobile radio telephone system to show the radiating capability of the radio, still have a very poor service record. A valuable need is to provide an antenna which is mobile, yet which is also reliable.

UNITED STATES PATENT OFFICE

2,611,866

CYLINDRICAL ANTENNA

Andrew Alford, Cambridge, Mass.

Application June 19, 1946, Serial No. 677,654

20 Claims. (Cl. 250—33)

This invention relates to new and useful improvements in antennas and particularly in mobile transmitting and receiving antennas for use on automobiles, buses, trains, aircraft and the like. In the art of radio transmission where at least one station is mobile it is the general practice to employ vertically polarized radio frequency waves, since they have good field strength near to the ground.

A simple and widely used antenna for such waves is a vertical flexible whip antenna. This antenna has several serious shortcomings. In order to function efficiently it must be near to a quarter wave length long, a length at which it is resonant and has a narrow pass band. The pass band can be broadened by increasing the thickness of the radiating element but it then may cease to be a whip antenna and may present too rigid and hazardous a projection from a moving vehicle. The band width of an ordinary quarter wave whip antenna is of the order of ten percent (.10) and, even if compensating circuits are used, this can only be increased to approximately twenty-five percent (.25).

If the length of a whip antenna is reduced below a quarter wave length, then its radiation resistance will become materially lowered and its input impedance will include capacitive reactance. The expedient of tuning out this reactance with a coil will further decrease the efficiency of the antenna, and its already small band width.

Tilting a vertical whip antenna away from its perpendicular position, so as to lower the height of its tip, will diminish both its band width and radiation resistance. At the relatively high frequency of 156 mc., a quarter wave length whip would be all of 16 inches long. A 16-inch protrusion from the top of a vehicle as high as a bus, or a truck, or a railroad car can be very troublesome. Such vehicles frequently are built nearly as high as the minimum head room tolerance legally permitted for bridges, tunnels, viaducts and terminals. Moreover, in certain areas such obstructions would most likely encounter low hanging branches of trees.

Foldable mounting of a whip antenna to avoid overhead obstacles will make continued use of the associated radio equipment impossible. Furthermore, such a mounting, as well as one permitting the whip antenna to tilt when striking an object, will necessitate complicated and expensive flexible feed line means and will add to servicing requirements.

A whip antenna attached to some part of a ve-

hicle would be subject to damage when it is in contact with overhead obstructions, such as trees, telephone wires, bridge railings, etc. and to damage when it is in contact with the ground.

It is an object of this invention to provide a

radiating element which is mobile, yet which is

reliable, and which is also compact and

inexpensive to manufacture and to install.

It is another object of this invention to provide

a radiating element which is mobile, yet which is

reliable, and which is also compact and

inexpensive to manufacture and to install.

It is a further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.

It is a still further object of this invention to provide

a radiating element which is mobile, yet which is

reliable, and which is also compact and

inexpensive to manufacture and to install.</

Fig. 2 is a transverse cross sectional view of the antenna shown in Fig. 1; and

Fig. 3 is a corresponding cross sectional view of a modified form of the antenna shown in Figs. 1 and 2.

Referring now more particularly to Fig. 1, the radiating element shown therein consists of a cylindrical body element 10, which may be a metallic casting or spinning shaped like a pie plate. This element has a top disc 2, and a rim 1 attached thereto. The cylinder is joined by a tube 3 which is mechanically attached to inside surface of top 2 at substantially its center. In practice tube 3 may be formed as an integral part of element 1, 2. Tube 3 may be of metal and as a result will be conductive. However, the inside portion of tube 3 joins areas of the outer side of disc 2 where R. F. voltages are of zero (or extremely low) potential and, therefore, the inside may be non-conductive without preventing this device from functioning. On the other hand, it will do no harm if the inside of tube 3 is a good conductor and, despite that, leakage voltages passing from the radiator to tube 3 will be small due to the voltage null on the outer surfaces of this radiator near its center. This is not true of the outer surface of tube 3. This surface, which is part of the inner area of the hollow cylinder should be conductive as there must be a low impedance axial connection between the inner surfaces of cylinder 1, 2 and a ground plate 4 on which the lower end of tube 3 is mounted. Where a metallic supporting mast is used the portion of it which passes through the hollow cylinder 1, 2 may take the place of tube 3. Its outer skin will perform this conductive function and there will be no need for tube 3, except that 3 ordinarily serves as a convenient gauge for properly spacing the cylinder from the plate 4.

Tube 3 is of such length and is so arranged that the cylinder 1, 2 and plate 4 do not touch each other; it holds them parallel and the rim of the cylinder evenly separated by gap 6. Gap 6 may be an air gap and is so shown in the drawing. However, it may be physically sealed by a dielectric substance so long as the area of the gap still remains non-conductive, in the ordinary sense, and constitutes a hiatus in the conductive surfaces of the cylinder wherever it intercepts them. Gap 6 is short-circuited by a radial metal plate 5 within the cylinder extending from tube 3 to rim 1 and contacting plate 4.

The entire structure 1-5 may be described as a hollow body or cylinder whose ends are closed by disc 2 and plate 4, and whose side wall has a gap 6 which runs around the cylinder in a plane parallel to and midway between disc 2 and plate 4 and returns on itself.

The hollow cylinder may be made of solid sheet metal (or an equivalent such as solid sheet plastic including a conductive layer) and, accordingly, the inner and outer areas, will comprise wall surfaces physically unbroken except for gap 6. However, this physical continuity is not necessary, and the device will operate satisfactorily if made of wire screen or of perforated sheet metal if the openings are not too large with respect to one wave length corresponding to the highest operating frequency, e. g. not larger than 1/100 of a wave length.

The antenna is energized over a coaxial transmission line having an outer conductor 8 and inner conductor 9. Inner conductor 9 is connected to the edge of the rim of body element 1, and the outer conductor 8 is connected to plate 75 ground.

4 in which a hole 7 is formed for its passage. These connections are made at points opposite each other across gap 6 and this part of the gap is at a place on the side of the hollow cylinder which is diametrically opposite the position of short circuiting bar 5.

When the antenna is energized the edges of gap 6, constitute a balanced transmission line. For the purposes of this application and of the 10 claims herein the expression "transmission line," if not qualified by the term "coaxial," will refer to the transmission line formed by the edges of gap 6. The hollow body portion of this antenna (which may be further described as surrounding 15 and enclosing a toroidal space about the outer perimeter of which gap 6 is located) has distributed inductive reactance which is shunted across this transmission line. The magnitude of this distributed reactance depends primarily on 20 the area of a transverse cross section, taken in the plane of bar 5, of the toroidal space on one side of tube 3. This is the space between the inner surfaces of elements 1, 2, the outer surface of tube 3 and the top surface of plate 4. If the 25 inside diameter of the hollow cylinder is designated as D, the outer diameter of the tube 3 as d, and the distance between the inner surfaces of top 2 and plate 4 as H, then this cross sectional area may be calculated by using the formula

$$A = \frac{(D-d) \times H}{2}$$

Certain cylinders, which have proper magnitudes of distributed reactance and perform in a preferred manner as radiators in accordance with this invention, have such dimensions that, when converted into wave lengths, the area derived by solving the equation is $A = .00435\lambda^2$.

40 Short-circuiting band 5 causes nearly complete reflection of incident waves traveling along gap 6 around both sides of the hollow cylinder toward it. The interference between incident waves and reflected waves results in a standing wave distribution of voltage across gap 6.

One minimum of voltage across the gap occurs at shorting bar 5; two maxima of voltage 45 occur at points on opposite sides of the hollow cylinder each of which is about midway between bar 5 and the feed point. Under certain conditions, two additional voltage minima, which ordinarily are undesirable, may occur on gap 6. They will be between bar 5 and the feed point and are likely to be near to, and on each side of, the feed point. A condition which may cause this is that the gap is too long (the circumference of the cylinder) in proportion to the cross sectional area A and that therefore the velocity of propagation along the gap is not great enough 50 for the gap length.

When the only voltage minima are at the shorting bar and the feed point, the voltage differences across gap 6, though they vary in magnitude, are in the same phase, and currents moving between the edges of gap 6 and the surfaces 55 2 and 4 move in the same direction.

It has been empirically ascertained in actual 60 tests, and it can be further demonstrated in other ways, that this in-phase condition of the R. F. voltages across gap 6 and the geometric shape 65 of the hollow cylinder will cause this element to act as a horizontally omnidirectional radiator of vertically polarized energy, assuming, of course, that the axis of tube 3 is perpendicular to the 70 ground.

When undesired voltage minima occur between the feed point and bar 5 (along the gap 6 on each side of the hollow cylinder), the phases of the R. F. voltages near those minima shift rapidly. This alters the current distribution pattern and results in asymmetry of the horizontal radiation pattern. The hollow cylinder should preferably be so proportioned that the distances from bar 5 to the first voltage minima (or to imaginary positions of the first minima constructively existing beyond the feed point) in each direction around the hollow cylinder, are equal to (or greater than) one-half of the circumference of the cylinder.

The desired standing wave condition can be obtained even when gap 6 is greater than $\lambda/2$ in length by sufficiently increasing the velocity of propagation along the gap, even substantially beyond the speed of light under certain conditions. This is controlled in part and within limits by the cross sectional area described above and by the capacity per unit length between the edges of the gap.

A cross sectional area $A = .00435\lambda^2$ together with a gap which is of the order of $.0048\lambda$ wide and is formed between a thin metal edge and a plate, results in a velocity of propagation along the gap about 20 percent greater than the velocity in free space. This permits the use of a cylinder whose circumference is proportionally increased so that each half circumference is in the neighborhood of 20 percent more than a half wave length. That is

$$\frac{\pi D}{2} = \frac{1.2\lambda}{2} \text{ or } D = .38\lambda$$

The physical enlargement of the hollow cylinder with respect to the operating wave length, which is effected at the same time that undesired voltage minima are averted, will make its input impedance low enough to match a 50-ohm co-axial line. Thus, in addition to being compact and vertically polarized (when properly positioned with respect to the earth) the device requires no input transformer, making it an ideal coupling between a 50-ohm cable and the radiation resistance of space. One example of satisfactory proportioning of the several parts of the antenna may be offered by suggesting the following dimensions: $D = 442\lambda$, $d = 273\lambda$, $H = .051\lambda$, and $g = .045\lambda$. These dimensions are, unless otherwise specified, expressed in terms of a wave length corresponding to the middle frequency of the operating band of frequencies.

It should be borne in mind that the controlling geometric characteristic for a gap which has a fixed amount of distributed capacitance per unit length, is the cross sectional area described above. For example, d may be made larger with respect to D , reducing the value of $D - d$, but by increasing H by an easily determined amount, A will remain substantially the same and the standing wave condition will be substantially unchanged.

Moreover, the hollow cylinder may be shaped so that its toroidal cross section on each side of the central tube is of other shapes than rectangular. This cross section may be circular, elliptical or irregularly shaped. In the same manner, it is not essential that cross sections of the hollow cylinder, taken in planes perpendicular to the axis of tube 3 should be circular. The important factors are that A be generally of the order of one-half a hundredth λ^2 , and that the exact value of A can vary depending upon the capacitive characteristics of the gap. In this applica-

tion, and in particular in the claims, the word "cylinder" is used in a broad sense to indicate all hollow structures which electrically control with the requirements of the invention though they are not necessarily geometric cylinders having circular transverse cross sections.

The antenna produces substantially circular radiation patterns in horizontal planes, i. e. planes perpendicular to the axis of tube 3, and figure-of-8 vertical patterns in planes passing through that axis. The band width of the antenna is of the order of 1.2.

Obviously the antenna described above may be employed at frequencies and for purposes other than those given above by way of exemplification.

The conductive ground plane 4 may be a metal sheet attached to the roof of a vehicle or forming an integral portion thereof. It does not necessarily have to be perfectly flat. As an analogous example, it is known that a ground plane of finite physical size, above a certain limit, will behave like an infinite reflective plane and affect the radiation patterns of any radiator associated with it. A physically infinite plane is unnecessary. Similarly, a physically substantially flat plane will, at ordinary wave lengths, behave like a perfectly flat ground plane. Therefore, the curved metal roof of a vehicle may serve as ground plane 4.

It is obvious that ground plane 4 will affect the vertical distribution pattern of the radiator. However, this is not a disadvantage. If the antenna is close to the earth, e.g. on the roof of a bus, the areas masked by the ground plane will be unimportant. Even if the antenna is not close to the earth, i. e. if it is in an airplane, the vertical masking is not a disadvantage. For in an aircraft installation, the radiating element could be installed on the underside of the surface acting as a ground plane. The important patterns, those in horizontal planes, are not appreciably affected.

In the embodiment shown in Fig. 3 the gap is not located near to the ground plane, but in the edge of the rim which is closest to disc top 2 (which corresponds to disc top 2 of Fig. 2) and farthest from the ground plane 4.

The non-conductive space inside the hollow cylinder need not necessarily be filled with air. Instead, other dielectrics may be used including dielectrics which are gases, liquids and solids. However, substances whose dielectric constants differ from that of air will increase the distributed capacity and reduce the velocity of propagation. The proportions of the hollow cylinder should, therefore, be somewhat altered. Other changes and adaptations will readily suggest themselves to those skilled in the art.

The shorting element which has been described in the present application as located on the side of the slot diametrically opposite to the feed point need not in practice be of exactly zero impedance. The terms "short circuit" and "short-circuiting element" as used herein, both in the description and in the claims, are intended to include low impedance terminations, such as a wire or coil having low inductance, which are capable of producing substantial percentages of reflection.

Moreover, it is also within the scope of this invention that another feed line be connected at the point designated for the location and in lieu of the shorting element. The desired standing wave condition on the gap or slot can be produced

with this two feed point arrangement just as well as by one in which there is a single feed point and a reflection point or low impedance point diametrically opposite to it. It has been found that usually a double feed affects the operating characteristics of the antenna by broadening the operating frequency band.

In accordance with the principles described herein the proportions of the antenna affect both the radiation patterns and the input impedance. In certain embodiments where a very close approximation to a circular horizontal radiation pattern is desired, it may be necessary in order to achieve this to use proportions which result in a reactive component. This component remains nearly constant over a wide band of frequencies and, therefore, can be avoided by a fixed series condenser.

What I claim is:

1. An antenna in combination with means providing a flat conductive surface comprising a hollow conductive body having a peripheral rim spaced closely to the conductive surface forming an air gap between the conductive surface and the peripheral rim in which the material in the peripheral rim adjacent the air gap forms one side of a transmission line and the material in the conductive surface opposite said rim forms the other side of the transmission line, said air gap having a width not substantially greater than $.045\lambda$ where λ is a wave length corresponding to a frequency within the operating band of transmission means within the hollow body supporting the same from said conductive surface and conductively connecting the hollow body with said conductive surface and a feeder having one conductor connected to one side of the transmission line and the other conductor connected to the other side of the transmission line said hollow body having an inside diameter which is substantially not less than $.38\lambda$.

2. The antenna according to claim 1, having a shape in which the transmission line forms a closed loop.

3. The antenna according to claim 1, in which the hollow conducting body has a circular perimeter whereby the transmission line forms a circular loop.

4. The antenna according to claim 1, in which the surface and edge of the rim are in different planes closely spaced one from the other.

5. The antenna according to claim 1, having a shape in which the transmission line forms a closed loop, and having a short circuit means across the line at a point half the way around the loop from where the terminals of said feeder are connected.

6. The antenna according to claim 1, and in which the rim forming a part of the transmission line has the shape of a short cylinder, and short circuit means across the line substantially diametrically opposite the point of connection of the feeder.

7. An antenna comprising a conducting cylinder open at one end, a conducting surface, means providing a conductor extending axially within the cylinder and having one end fastened to said surface and holding the cylinder with the edge of the open end thereof in spaced relationship to said conductive surface to form a gap between them, the cross sectional area of the space within the cylinder taken in a plane containing its axis and on one side of the conductor being substantially one-half of one-hundredth of a wave length squared corresponding to the center fre-

quency of the operating band, a feeder having two conductors one conductor connected with the surface and the other conductor with the cylinder near said gap, and short circuit means across the gap at a point diametrically opposite the points of connection of the transmission line.

8. An antenna comprising a metal cylinder open at one and closed at the other end, said cylinder having a circular cross section, a plate providing a metal surface, a metal tube extending axially within the cylinder and having one end fastened to the closed end thereof and the other end to the surface holding the latter in spaced relationship with the edge of the open cylinder end to form a circular gap between them, the cross sectional area of the toroidal space within the cylinder taken in a plane containing the axis of said tube and on one side thereof being substantially one-half of one-hundredth of a wave length squared corresponding to the center frequency of the operating band, a feeder having two conductors with one conductor connected with the plate and the other conductor with the cylinder near said gap, and short circuit means across the gap at a point diametrically opposite the points of connection of the feeder.

9. An antenna comprising a metal cylinder open at one and closed at the other end, said cylinder having a circular cross section, a metal plate, a metal tube having one end fastened to the closed end of the cylinder and the other end to the plate and holding the edge of the open cylinder end above the plate to form a gap between the edge and the plate, a transmission line having one conductor connected with the plate and the other conductor with the cylinder near said gap, and short circuit means across the gap at a point diametrically opposite the points of connection of the transmission line.

10. The antenna according to claim 9, and in which the cross sectional area of the toroidal space within the cylinder taken in a plane containing the axis of said tube and on one side thereof is substantially $.0043\lambda^2$ where λ is the wave length corresponding to the center frequency of the operating band.

11. An antenna comprising a metal cylinder open at one and closed at the other end, said cylinder having a circular cross section of a diameter of about one-half a wave length corresponding to the center frequency of the operating band, a metal plate, a metal tube having one end fastened to the closed end of the cylinder and the other end to the plate holding the edge of the open cylinder end above the plate, the circular gap between the edge and the plate being a small fraction of a wave length wide, a transmission line having one conductor connected with the plate and the other conductor with the cylinder at the gap, and short circuit means across the gap at a point diametrically opposite the points of connection of the transmission line.

12. An antenna comprising a metal cylinder $.05\lambda$ high where λ is the wave length corresponding to the center frequency of the operating band, said cylinder being open at one and closed at the other end, said cylinder having diameter substantially $.44\lambda$, a metal plate, a metal tube having a diameter substantially $.27\lambda$ and having one end fastened to the closed end of the cylinder and the other end to the plate thereby holding the edge of the open cylinder end above the plate at a distance to form a gap substantially $.045\lambda$

wide between the edge of the cylinder and the plate, a concentric transmission line having the outer conductor connected with the plate and the inner conductor with the cylinder near said gap, and a short circuit means across the gap at a point diametrically opposite the points of connection of the transmission line.

13. An antenna comprising a metal cylinder, a metal plate closing and supporting one end of the cylinder, a metal tube axially positioned within the cylinder having one end fastened to the plate, a disc having substantially the same area as a transverse cross section of the cylinder carried by the other end of the tube and held by it at a distance from the edge of the open cylinder end parallel with the plate to form a circular gap, a transmission line having one conductor connected with the disc and the other conductor with the cylinder near said gap, and a short circuit means across the gap at a point diametrically opposite the points of connection of the transmission line.

14. The antenna according to claim 13, and in which the cross sectional area of the space within the cylinder taken in a plane containing the axis of said tube and on one side thereof is substantially one-half of one-hundredth of a wave length squared, the wave length corresponding to the center frequency of the operating band.

15. The antenna according to claim 13, and in which the plate is larger in area than the transverse cross sectional area enclosed within the perimeter of the cylinder.

16. The antenna according to claim 13, and in which the cross sectional area of the toroidal space within the cylinder taken in a plane containing the axis of said tube and on one side thereof is substantially one-half of one-hundredth of a wave length squared which corresponds to a frequency within the operating band, and the transmission line projects through a hole in the plate adjacent the side wall of the cylinder.

17. An antenna comprising a metal cylinder open at one end and closed at the other end, said cylinder having a circular cross section, a metal disc, a metal tube having one end fastened to the closed end of the cylinder and the other end

to the disc and holding the disc above the edge of the open cylinder end but spaced therefrom to form a circular gap between the edge and the disc, a transmission line having one conductor connected with the disc and the other conductor with the cylinder near said gap, and a short circuit means across the gap at a point diametrically opposite the points of connection of the transmission line.

10 18. In an antenna, a hollow cylinder having closed ends and a gap formed in the cylindrical wall at one end in the form of a loop, connection means between the ends near the axis of the cylinder, means for feeding the cylinder near the gap, and short circuit means across the gap, the distances from said short circuit means along the gap to said feed point being less than the normal distance from the short circuit to the point where a voltage minimum would occur.

15 19. In an antenna, a hollow cylinder having closed ends and a gap formed in the side wall at one end in the form of a loop, connection means between the ends near the axis of the cylinder, means for feeding the cylinder near the gap, and short circuit means across the gap at substantially the same distance from the feed point measured in opposite directions along the gap, said distance being less than that necessary to establish a voltage minimum along the gap.

20 20. The antenna according to claim 1, having a low impedance radio frequency reflecting means across the transmission line at its mid-point from the connection of the feeder across the transmission line.

30 35 ANDREW ALFORD.
